UNITED STATES PATENT OFFICE

MAX HALPERN, OF BRONX, AND WILLIAM MAYER, OF BROOKLYN, NEW YORK

NECKTIE

Application filed November 6, 1929. Serial No. 403,240.

This invention relates to neckties of the bow type variety and is an improvement over the invention shown and described in our copending application, Serial No. 340,5440, filed February 16, 1929 Patent Number 1,759,007.

The main object of this invention like that set forth in the above mentioned application is to provide a means within the wings of the tie to hold the same in an expanded condition to prevent sagging or wrinkling regardless of the abuse the tie might receive during the life thereof.

Another object of the invention is to provide an inner lining for the wings of the bow tie of the ready type variety which includes a relatively stiff body of material of a shape similar to the shape of the wings and which has stitched thereto adjacent opposite ends, a pair of elastic tabs, the said tabs extending beyond the ends of the stiffening body and adapted to be bent upon themselves to maintain the wings in a full expanded condition. In addition to this structure we provide an extra layer of stiffening material of a reduced width to that of the body, the ends of the reduced strip overlapping the fixed ends of the elastic tabs to materially increase the stiffness of the wings inward of the edges thereof.

With these and other objects in view, the invention resides in the certain novel construction, combination and arrangement of parts, the essential features of which are hereinafter fully described in the annexed specification, are particularly pointed out in the claims and are illustrated in the accompanying drawings, in which:

Figure 1 is a perspective view of a ready tied bow tie equipped with our invention.

Figure 2 is a plan view of the wing stiffening member.

Figure 3 is an enlarged detail horizontal sectional view through one of the front wings of the tie taken on the line 3-3 of Figure 1.

Referring to the drawings by reference characters, the letter A designates the usual neck band of a ready made bow tie, while B designates the usual double wing back member of the tie, and C the usual double wing

front member of the tie, both of which wing members are of gradually narrowing width toward their centers and are secured thereto by a piece of material representing the knot D. Usually, in ties of this character, 55 the front double wing members C consist of an inner and outer ply of material joined together at their edges or a single length of material folded over and stitched at their upper and lower edges, between which the 60 usual heavy lining is interposed.

In carrying out our invention, we provide a strip of relatively stiff material such as buckram or canvas 5 in lieu of the usual lining and which is shaped similar to the 65 double wing shape of at least the front double wing C of the tie. The width of this lining 5 as well as the length thereof is slightly greater than the width and length of the double wing member C, while intermediate 70 the ends of the lining strip 5 and at opposite points along the edges thereof, are transverse narrow incisions or V-shaped notches 6-6, these incisions being of a length dependent upon the tightness of the knot D. 75 Arranged longitudinally upon the lining strip 5 at opposite ends thereof are strips of relatively thin rubber or other elastic material 7-7 which are stitched to the lining strip 5 intermediate their ends by single or 80 double rows of transverse stitching 8. Lying flat against one side of the lining strip or body 5 is an elongated strip 9 of a similar material but of a less width and length than the body 5 so as to be disposed within the 85 confines of the edges thereof. The opposite ends of the strip 9 overlap the inner ends of the elastic tabs 7, and the said ends are secured by one of the rows of stitching 8.

During the manufacture of the double wing C, the lining strip or body 5 having the rubber tabs 7 and reinforcing strip 9 associated therewith is placed between the front and back walls of the wing member, and stitched thereto, the inwardly converging 95 edges of the lining strip or body being first folded upon themselves and which is accomplished by reason of the incisions or notches 6-6. Also during the formation of the double wing C, the ends of the lining 5 will be 100

flexed inwardly adjacent the rows of stitching 8 which will result in the turning over of the rubber strips or tabs 7—7 directly intermediate their ends as clearly illustrated in Figure 5 of the drawing. Consequently the ends of the strips or tabs 7—7 which are unsecured to the wing members of the tie will automatically tend to move outwardly expanding the front and back walls of the double wing member C to impart a full appearance thereto, and to prevent the crushing of the tie in either a transverse or longitudinal direction. Although it is unnecessary to insert one of the linings 5 in the back wing members B, the same may be inserted if desired.

Having thus described the invention, what we claim as new and desire to secure by Letters Patent is:—

1. A lining insert for bow ties comprising a flexible body of a shape conforming to the shape of the wing of a bow tie, elastic tabs stitched to the ends of said flexible body, and extending therebeyond, and a relatively stiff strip of reinforcing material of a length and width less than the width and length of the body and disposed on one side of said body, the ends of said reinforcing strip overlapping said elastic tabs, and stitching passing through the overlapping ends of said reinforcing strip, elastic tabs and body, substantially as and for the purpose specified.
2. A lining insert for bow ties comprising a flexible body of a shape conforming to the shape of the wing of a bow tie, flexible elastic tabs secured to the ends of said flexible body and extending therebeyond, a relatively stiff strip of reinforcing material secured to one side of said flexible body, the ends of said reinforcing strip overlapping said flexible tabs, and securing means passing through the overlapping ends of said reinforcing strip, flexible tabs and body, substantially as and for the purpose specified.

In testimony whereof we affix our signatures.

MAX HALPERN.
WILLIAM MAYER.
